US00D553597S

(12) **United States Design Patent** (10) **Patent No.:** **US D553,597 S**
Hsu (45) **Date of Patent:** **** Oct. 23, 2007**

(54) **MOBILE COMMUNICATIONS DEVICE**

(75) Inventor: **Elliott Hsu**, Raleigh, NC (US)

(73) Assignee: **Sony Ericsson Mobile Communications AB**, Lund (SE)

(**) Term: **14 Years**

(21) Appl. No.: **29/251,123**

(22) Filed: **Jan. 4, 2006**

(51) **LOC (8) Cl.** **14-03**

(52) **U.S. Cl.** **D14/138**

(58) **Field of Classification Search** D14/496, D14/138, 341-347; 455/575.3, 575.1; D21/517
See application file for complete search history.

(57) **CLAIM**

The ornamental design for a mobile communications device, as shown and described.

DESCRIPTION

FIG. 1 is a front right perspective view of a mobile communications device in a closed position showing my design;

FIG. 2 is a front view thereof;

FIG. 3 is a right side view thereof;

FIG. 4 is a left side view thereof;

FIG. 5 is a rear view thereof;

FIG. 6 is a top view thereof;

FIG. 7 is a bottom view thereof;

FIG. 8 is a front right perspective view of the mobile communications device of FIG. 1 in an open position;

FIG. 9 is a rear left perspective view thereof;

FIG. 10 is a front view thereof;

FIG. 11 is a right side view thereof;

FIG. 12 is a left side view thereof;

FIG. 13 is a rear view thereof;

FIG. 14 is a top view thereof; and,

FIG. 15 is a bottom view thereof.

The broken lines shown in the drawing that are immediately adjacent to the shaded areas and define unshaded regions represent the bounds of the claimed design, while all other broken lines are directed to environment and are for illustrative purposes only; the broken lines form no part of the claimed design. Unshaded regions defined by encompassing broken or solid lines are not part of the claimed design.

1 Claim, 5 Drawing Sheets
